UNITED STATES PATENT OFFICE

123,650

DESIGN FOR A DRESS ENSEMBLE

Anna Louise Siverts, New York, N. Y.

Application July 31, 1940, Serial No. 94,078

Term of patent 3½ years

To all whom it may concern:

Be it known that I, Anna Louise Siverts, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design;

Fig. 2 is the rear view thereof.

Fig. 3 is a front view of the dress member of the ensemble shown in Figs. 1 and 2, and

Fig. 4 is the rear view of Fig. 3.

The characteristic feature of my design resides in the combination on the ensemble disclosed of the specific plaid jacket member which is shaped as shown in association with the specific two-toned shirt-waist dress having cord trimming edging the round collar member and the belt member, all as shown.

I claim:

The ornamental design for a dress ensemble, substantially as shown and described.

ANNA LOUISE SIVERTS.
